PIPE CLEANING MACHINE

Ben L. Colchensky, Okmulgee, Okla., assignor to
New Deal Specialty Company, Inc., Okmulgee,
Okla., a corporation of Oklahoma

Application December 17, 1934, Serial No. 757,927

9 Claims. (Cl. 15—104.04)

This invention relates to a pipe cleaning machine and is an improvement over copending application, No. 710,362. It is an object of the invention to provide a machine of this character which will more satisfactorily, more quickly, and efficiently, remove dirt, rust, scale or other foreign accumulation from the exterior surface of a pipe or tube.

Another object of the invention is to provide a pipe cleaning machine which can be operated with safety and which can be set and a pipe passed through and cleaned without the attention of an attendant.

Another object of the invention is to provide a machine of simple and inexpensive construction, which can be easily transported, which is constructed to be adjusted to accommodate pipe of various sizes and having selective single and dual rollers designed to perform a double function of both guiding and cleaning the pipe in its passage through the machine.

A further object of the invention is to provide cleaning elements having cutting blades which can be easily detached and replaced in the field.

Other objects and advantages will be apparent from the following description taken in connection with the accompanying drawings, wherein

Fig. 1 is a side elevation illustrating one application of the invention;

Fig. 2, a front elevation;

Fig. 3, a perspective taken from the rear, and

Fig. 4, a perspective from the front.

Referring to the drawings a frame 10 is formed of uprights and cross members of angle iron or other construction. On the frame 10 a pair of cutting elements 11 are mounted on parallel shafts 12, said cutting elements having parallel removable cutting blades 13 fastened in place by a pair of bolts 14 at each end of each blade. Each of the cutting elements is provided with a sprocket 15 driven by a chain 16 from a sprocket 17 mounted on a drive shaft driven from a source of power (not shown) by means of the pulley 19. When the pulley 19 is driven the cutting elements 11 are both rotated in the same direction so that a pipe or other substantially cylindrical body 20 resting upon the upper surface of the cutting element in contact with the same will be rotated.

In order to maintain the work, that is, pipe 20 in contact with the cutting elements and exert sufficient pressure against the pipe to cause it to be properly cleaned, an adjustable lever or presser bar 21 is provided. The lever 21 is formed of spaced side bars and carries a pair of guiding and cleaning rollers 22 on one side and a single, slightly smaller guiding and cleaning roller 23 on its other side or disposed opposite the guide rollers 22. The guide rollers 22 are supported by a bracket 24 and the guide roller 23 is supported by a bracket 25, the brackets 24 and 25 being at-

tached to the spaced side bars which form the presser bar 21. The rollers 22 and 23 are mounted to rotate on spindles 26 and 27 and are grooved to cause the pipe being cleaned to be fed through the machine more quickly.

When a large pipe is being cleaned it will be rotated by the cutting elements 11, and the rollers 22 will bear against the pipe and guide the same. These rollers 22 will also press the pipe against the rotating cutting elements. The rollers 22 will not only guide the pipe and press the same against the cooperating cutting elements but will perform a cleaning action. If a small pipe is being cleaned the roller 23 will engage the pipe and perform a similar dual function such as that just described.

In order to cause the pipe to travel through the machine, the guiding rollers which are normally disposed parallel to the cutting rollers 11 are shifted slightly. To make such angular adjustment possible the presser bar or lever 21 has one end pivotally mounted in a manner to permit the rollers 22 to be raised and lowered and at the same time adjusted angularly to permit the axis to be changed out of a position parallel with the axis of the cutting elements 11, the latter serving to cause the traveling of the work through the machine in either direction depending upon the angle of adjustment.

The pair of spaced plates which form the presser bar or lever 21 are connected at one end by a cross member 28 which is adjustable on an upright post 29, a set screw 30 being provided for securing the cross member in proper position. The post 29 is provided with a flattened side having a plurality of set screw receiving depressions 31. The shaft 29 is supported in bearing brackets 32 mounted in spaced relation on the frame 10. A set screw attached collar 33 permits vertical adjustment of the shaft 29, said collar maintaining the shaft in a definite position. A similar collar 34 limits the upward movement of the shaft and in order to permit a limited resilient upward movement a spring 35 is confined between the collar 34 and the underside of the bracket 32 on the frame of the machine.

The post or shaft 29 is located at the rear of the machine and at the front of the machine the presser bar or lever 21 is connected to a similar upright post or shaft 36 carried by an adjustable bracket 37 slidable axially of the cutting elements carried by the machine to give the lever 21 a swinging movement about the post 29 as a pivot. The post or shaft 36 is provided with a pair of set screw collars 38 which can be set at the desired position for the proper vertical adjustment of the post 36. When the upper collar engages the bracket 37 it limits downward movement of the shaft 36 while the lower collar 60

38 limits the upward movement of said shaft. A spring 39 performs a function similar to the function of the spring 35 in permitting a certain amount of resilient movement upward of the 5 shaft 36 to permit a bump or coupling to pass the cutters.

The upper end of the shaft 36 is connected to the presser bar or lever 21 by an adjustable connection including a manually operable lever 10 which when thrown in one position maintains the front end of the presser bar in its lowermost position with the rollers in contact with the work and when thrown in another position maintains the front end of the presser bar in its uppermost 15 position, with the rollers out of contact with the work.

As shown particularly in Fig. 4 the side bars of the lever are connected by a lost motion connection at their front ends by a cross member 40 20 slidable on the shaft 36, such lost motion connection being formed by bolts or studs in the cross member extending through slots in the side bars. The ends of the cross member are connected by means of pivotally connected links 25 41 and 42 with a second or upper cross member 43 fixed on the upper end of the shaft 36 by one or more set screws 53, two of which are shown in Fig. 1, but only one in the other figures. A handle 44 is carried by the links 42 which handle and 30 links 42 form in effect a bell crank lever for shifting the links from the position shown in Figs. 3 and 4 to the position approached by the showing of Fig. 1, so that when the handle is 35 swung 180° and overlies the lever 21 the links 42 are inverted and consequently the distance between the cross members 40 and 43 is shorter.

In order to change the angle of the rollers 22 relative to the cooperating cutting elements the bracket 37 carrying the shaft 36 is slidable 40 along the frame of the machine. This bracket has its upper arm extending over the inner edge of the machine frame on which it is mounted and has its lower edge provided with a similarly extending element whereby the bracket is prevented from becoming disengaged from the frame but is free to slide laterally thereon.

In order to provide for the necessary sliding movement of this bracket 37 a lever 45 (see Fig. 4) is pivoted at 46 on the machine frame and is connected by means of a link 47 with the bracket 37. Swinging of the lever 45 on its pivot 46 will move the bracket 37 and produce the desired angle of adjustment of the rollers 22. In order to fasten the bracket 37 in fixed position a clamping screw 48 is provided and a crank 49 is carried by the screw for manipulating the same. A brush 50 is provided for cleaning the pipe after it has been subjected to the rotating cutters. This brush 50 is driven (see Fig. 3) in any desired 60 manner as for example from one of the chains 16 which drive the rotary cutters. The chain engages a sprocket fixed to stub shaft 51, connected to drive the brush by means of the belt 52.

In operation, when a pipe of 2 inches or larger 65 in diameter is to be cleaned this pipe is placed between the rollers as shown in Fig. 4, the handle 44 being thrown over beyond the position in which it is shown in Figure 1 substantially 180° to permit the pipe to be inserted, then the handle is brought 70 forward into its lowermost position as shown in Figs. 3 and 4 to bring the rollers 22 into contact with the pipe. Rotation of the supporting cutters 11 will produce rotation of the pipe being cleaned and this rotation will impart rotation to the 75 rollers 22 which will guide and clean the pipe.

The cutters 22 being set at the proper angle by shifting of the bracket 37 by means of the handle 45 will cause the pipe to travel through the machine. When the handle 45 is swung to the left the pipe will travel to the right and when the handle 45 is swung to the right the pipe will reverse itself and travel backwardly or to the left. 5

When it is desired to clean a pipe of an external diameter considerably less than 2 inches the 10 presser bar or lever 21 is reversed to bring the guiding and cleaning rollers 23 into contact with the pipe where it will operate to guide the pipe through the machine and clean the same as well as cause travel of the pipe through the machine. To produce this reversal or inversion of the bar 15

21 the cross member 43 can be released by loosening set screw 53 from the front shaft or post 36 and the lever swung on the cross member 28 as a pivot in a vertical plane 180° upwardly and to the rear of the post 29 and then swung, the post 29 20 being rotated, in a horizontal plane 180° about the post 29 until the lever 21 is brought back into operative position. If the entire front assembly be disconnected from the post 36 in the reversing 25 operation and connected again to the post 36, the extremity of the handle 44 will extend oppositely from that shown in Fig. 2. The presser bar or lever 21 may be disconnected from the cross member 40 and reversed in the manner just described and when reconnected will not invert the 30 handle 44.

The brush 50 will remove any loose dirt or particles on the pipe and if a shoulder or union is encountered the handle 45 may be operated to cause a brief reversing of the movement of the 35 pipe to clean behind such shoulder.

It will be readily understood how when the machine is set and a pipe is passing therethrough, attention by an attendant is unnecessary. Further, when an attendant is present the front 40 upright shaft or post 36 will prevent the pipe from being discharged or forcibly ejected forwardly which might cause injury to the attendant and any inequalities on the surface of the pipe are accommodated or compensated for by means of 45 springs 35 and 39 which give the presser bar or lever a resiliency at each end.

Should an inequality on the pipe or other means break or injure the cutting blades 13 the injured 50 blade or blades can easily be removed and replaced in the field by removing the two bolts or screws in each end of the blade.

By cutters as referred to in the claims, is meant 55 rotary cleaning elements of the character to produce rotation of the pipe to be cleaned by engagement therewith, the expression being intended to cover brushes of sufficient stiffness to produce the necessary rotation.

It will be obvious to those skilled in the art 60 that various changes may be made in my device without departing from the spirit of my invention and therefore I do not limit myself to what is shown in the drawings and described in the specification but only as indicated in the appended claims. 65

I claim:

1. A pipe cleaning machine comprising a frame, a lever extending across and above said frame and pivoted adjacent one end to said frame to swing in a substantially horizontal and a substantially vertical plane, substantially horizontal and parallel roller means and cutter means for engaging along opposite sides of a pipe to be cleaned, one of said roller and cutter means being mounted in said frame laterally of said pivot and 70 75

the other mounted on said lever intermediate its ends, means to drive one of said roller means and cutter means, a support mounted on the other side of the frame from the pivoted end of the lever to move along said frame axially of said cutter means, means connecting the support and the adjacent end of the lever to move the lever and to protect the operator against accidental discharge of the pipe laterally from the machine, and means to move said support to swing the connection and lever horizontally to feed the pipe.

2. A pipe cleaning machine comprising a frame, a lever extending across said frame from front to rear and pivoted adjacent its rear end adjacent the rear of the frame for swinging movement in a substantially horizontal plane, a connection slideable along the front of the frame and attached to the lever adjacent its front end to swing the same horizontally, cooperating roller and cutter means on said lever and frame transversely of said lever for engaging along opposite sides of a pipe to be cleaned, means for driving one of said roller and cutter means, and means for moving said connection for varying the relation of the roller and cutter means for feeding the pipe.

3. A pipe cleaning machine comprising a frame, a lever extending across said frame from front to rear and pivoted adjacent its rear end adjacent the rear of the frame for swinging movement in a substantially horizontal plane, a connection slideable along the front of the frame and attached to the lever adjacent its front end to swing the same horizontally, cooperating roller and cutter means on said lever and frame transversely of said lever for engaging along opposite sides of a pipe to be cleaned, means for driving one of said roller and cutter means, and means for moving said connection for varying the relation of the roller and cutter means for feeding the pipe, and means for securing said slideable connection in a predetermined position.

4. A pipe cleaning machine comprising a frame, a lever extending across the frame from front to rear and pivoted adjacent its rear end adjacent the rear end of the frame for swinging in a substantially horizontal and in a substantially vertical plane, a connection slideable along the front frame attached to the lever adjacent its front end to swing the same horizontally, cooperating roller and cutter means on said frame transversely of said end engaging along opposite sides of the pipe to be cleaned, means for driving one of said roller and cutter means, and means for moving such connection relative to the roller and cutter means for feeding the pipe.

5. A pipe cleaning machine comprising a frame, a lever extending across said frame from front to rear and pivoted adjacent its rear end adjacent the rear of the frame for swinging movement in a substantially horizontal plane, a connection slideable along the front of the frame and attached by a lost motion connection to permit swinging movement of the lever to be produced by the sliding connection to the lever adjacent its front end to swing the same horizontally, cooperating roller and cutter means on said lever and frame transversely of said lever for engaging along opposite sides of a pipe to be cleaned, means for driving one of said roller and cutter means, and means for moving said connection for varying the relation

of the roller and cutter means for feeding the pipe.

6. A pipe cleaner comprising substantially parallel horizontally disposed cutters to receive a pipe to be cleaned along the same, means for supporting and driving said cutters, a lever pivoted at one side of said cutters for swinging movement in both a substantially horizontal and a substantially vertical plane, roller means on opposite sides of said lever intermediate its ends for selective engagement along the pipe whereby downward pressure on the lever will press the pipe against the cutters and swinging of the lever in a horizontal plane will cause the pipe to be advanced over said cutters said lever being reversible for bringing into operation the selective roller means by swinging the same at 180° in a single plane and 180° in a plane at right angles to the first.

7. A pipe cleaner comprising a frame, a lever extending across said frame from front to rear and pivoted adjacent the rear of the frame for swinging movement in a substantially horizontal plane, cooperating roller and cutter means on said lever and frame transversely of and intermediate the ends of said lever for engaging along opposite sides of a pipe to be cleaned, means for driving one of said roller and cutter means whereby downward pressure on the lever will press the pipe against the cutter means and swinging the lever in a horizontal plane will cause the pipe to be advanced over said cutter means, and means for accentuating the advance of the pipe by said roller means comprising a plurality of annular ridges in said roller means.

8. A pipe cleaning machine comprising a frame, a lever extending across said frame from front to rear and pivoted adjacent its rear end adjacent the rear of the frame for swinging movement in a substantially horizontal plane, a connection slideable along the front of the frame and attached to the lever adjacent its front end to swing the same horizontally, cooperating roller and cutter means on said lever and frame transversely of said lever for engaging along opposite sides of a pipe to be cleaned, means for driving one of said roller and cutter means, and means for moving said connection for varying the relation of the roller and cutter means for feeding the pipe, the connection slideable along the front of the frame and the lever being joined in a manner to permit yielding upward movement of the front end of the lever to permit an obstruction on the pipe to be cleaned to pass the cooperating roller and cutting means.

9. A pipe cleaner comprising a frame, a lever extending across said frame from front to rear and pivoted adjacent the rear of the frame for swinging movement in a substantially horizontal plane, cooperating roller and cutter means on said lever and frame transversely of said lever for engaging along opposite sides of a pipe to be cleaned, said means on the lever being disposed transversely of the same intermediate its ends and being constructed for selective engagement along the pipe whereby downward pressure on the lever will press the pipe against the cutters and swinging of the lever laterally will cause the pipe to be advanced from the cutters, said lever being movable on its pivot for bringing into operation the selective roller means.

BEN L. COLCHENSKY.
